UNITED STATES PATENT OFFICE.

WALTER R. REA, OF MINNEAPOLIS, MINNESOTA.

DEVICE FOR HANDLING CARDS OR SHEETS IN PRINTING-PRESSES.

1,179,757.

Specification of Letters Patent. Patented Apr. 18, 1916.

Application filed April 18, 1913. Serial No. 761,938.

To all whom it may concern:

Be it known that I, WALTER R. REA, a citizen of the United States, residing at Minneapolis, in the county of Hennepin and State of Minnesota, have invented certain new and useful Improvements in Devices for Handling Cards or Sheets in Printing-Presses, of which the following is a specification.

10 My invention relates to devices for handling cards or sheets in printing presses and has for its object to provide a new and improved means of receiving sheets or cards from the delivery side of a printing press when the same has a freshly-laid printed surface thereon, rolling said cards up with an extended sheet so that the parts thereof are held in non-slipping relation between two adjacent surfaces for preventing smudging while the ink is drying, in the same way as is accomplished by the ordinary and tedious method of hand-slip sheeting.

15 It is a further object of my invention to provide means coöperating with a roll having therein the sheets or cards, adapting said roll to operate as a feeding means to a press for other impressions upon the cards.

20 It is a further object of my invention to provide means for conducting the apron or sheet of said roll so that the same sheet may simultaneously operate to feed cards at one end of the press and receive and roll up the cards at the other end of the press.

25 The full objects and advantages of my invention will appear in connection with the detailed description thereof and are particularly pointed out in the claims.

30 In the drawings, illustrating the application of my invention in one form,—

35 Figure 1 is a side elevation showing diagrammatically a rotary press of common construction having my slip sheeting and feeding improvements attached thereto.

40 Fig. 2 is an enlarged side elevation of the forward part of the machine shown in Fig. 1. Fig. 3 is an enlarged side elevation with some parts in section of the rear end of the machine shown in Fig. 1. Fig. 4 is a plan view of the parts shown in Fig. 2. Figs. 45 5, 6, 7 and 8 are fragmentary views of details.

50 The frame 10 of a printing press of usual construction has the usual feed table 11 and delivery table 12. The only other parts of the printing press shown are the cylinder 13 and the inclined feed board 14. As shown

in Fig. 1, a rail system 15 is secured above the press which may be suspended from the ceiling or supported by separate framework 16 as desired. Upon the rear of the rail 15 is supported by means of rollers 17 a truck frame 18, said frame having depending hangers 19, said hangers formed with open-ended, downwardly-disposed slots 20 turned toward the front of the machine. The truck frame 18 is provided with a portion 21 extending below the rails 15, by means of which the truck frame 18 is secured in fixed position upon rails 15 by means of set bolt 22. Other trucks 22 are mounted to roll along rails 15 and are provided with hangers 23 having open-ended, oblique slots 24 turned toward the rear of the machine or toward the open end of the slots 20. The slots 20 and 24 are adapted to receive the 75 trunnions 25 of rollers 26, consisting of a central shaft or block upon which is wound a very extended strip or apron of paper or other fabric as may be desired. This strip may be of great length so that the complete 80 rolls may weigh as much as one thousand pounds or more, and the rolls are transformed from the hangers 23 to the hangers 19 by pushing the trucks 22 as close as possible to truck frame 18 and rolling the rolls 85 26 on the trunnions 25 out of the slots 24 and along bars 27 pivoted at 28 to the lower portion 29 of hangers 19, the free ends of said bars being adapted to rest upon retaining clips 30 on the lower ends of hangers 90 23. The slots 20 extend into an enlarged opening in the hangers 19 which are provided with bearing blocks 31, said bearing blocks being adjustable for wear by means of set screws 32 and 33 engaging said bearing blocks at right angles.

95 As shown in Figs. 1 and 5, a separate framework comprising a base 34 and a stand 35 is mounted upon casters 36. This framework is of substantially the same width as the frame of the printing press and is adapted to be secured in proper position relative thereto by means of arms 37 pivoted to the frame of the printing press and provided with hooks 38 adapted to engage over studs 100 39 on the base 34. A turn-buckle 40 in the arm 37 will adjust the position of the hooks 38 for holding the base 34 of the frame or truck in exactly the right position. The standards 35 have, projecting rearwardly 105 from the upper portions thereof, arm-like members 41 provided with arcuate, elong-

gated slots 42. A frame 43 is secured in fixed position upon the receiving table 12 of the printing press by means of clamps 44. The frame 43 has at the front end there-
 5 of a pair of standards 45, each of said standards having an offset boss 46. Links 47 are provided having at one end thereof pairs of longitudinal slots 48 and 49. Bolts 50 extend through slot 49 and pivotally se-
 10 cure the links 47 to the bracket portions 41. Other bolts 51 extend through slots 48 in links 47 and slots 42 in bracket portion 41, which bolts 51 lock the links 47 in desirable position of adjustment so that hooks 52 on
 15 the ends thereof will engage over the bosses 46 and hold the upper portion of the frame truck in fixed position relative to the press. A bolt 53 may, if desired, be threaded into a portion of standard 35 to contact with the
 20 end of link 47. The pair of links 47 have journaled therein a shaft 54 on which is a roller 55. The standards 45 have journaled therein a pair of rollers 56 and 57, roller 57 being held in contact with roller
 25 56 by means of springs 58 which are adjustable by hand screws or bolts 59. Standards 60 are provided at the rear end of frame 43 in which is journaled a fixed roller 61 cor-
 30 responding to roller 57. Link members 62 are pivotally secured by means of bolts 63 to backwardly extended portions 64 of standard 60. Slots 65 in the arc of a circle having its center at 63 are formed in standards 60, and by means of bolts 66 extending
 35 through said slots and the link members 62 said link members may be held in desired adjusted position. A roller 67 has its shaft 68 journaled in the ends of link members 62. A series of belts 69 run over rollers
 40 67 and 56, a corresponding series of belts 70 running over rollers 61 and 57. A shaft 71 is journaled in the lower front portion of truck frame 35, and said shaft is driven by a sprocket chain 72 running over a
 45 sprocket wheel 73 on shaft 71 and a sprocket wheel 74 on shaft 75, which is one of the driven shafts of the press. Shaft 71 has thereon a pulley 76 over which runs a belt 77, said belt driving shaft 78 of roller 57
 50 by means of which the lower set of feed belts 70 running over rollers 57 and 61 are constantly driven. A tightener bar 79 is adjustably secured to one of links 47 by means of a bolt 80 which extends through
 55 a slot 81 in said tightener bar, a pair of rollers 82 and 83 on said bar 79 engaging the two runs of belt 77. The shaft 71 has thereon a spur gear or pinion 84 meshing with a similar gear 85 on a shaft 86 jour-
 60 naled in uprights 35 adjacent shaft 71. Shaft 86 has thereon a rough-surfaced roller 87, also a sprocket wheel 88 outside of gear wheel 85. The sprocket wheel 88 is connect-
 65 ed by sprocket chain 89 with a sprocket wheel 90 having fast thereon a friction disk
 91 splined upon a short shaft 92. The shaft 92 has a bearing at its outer end in a bracket 93 offset from standard 35. The other end of shaft 92 has a bearing within a sleeve 94 upon which is a friction disk 95 corre-
 70 sponding to friction disk 91. The inner end of the sleeve 94 has a bearing within a boss 96 on the side of standard 35. The sleeve 94 is cut away along one side as indicated at 97, the bore of the sleeve then
 75 being in alinement with an open-topped bearing 98 in the top of standard 35, a similar open-topped bearing 98' being provided in the other standard. When the sleeve 94 is turned with the cutaway portion 97 up, the interior of said sleeve will form a bearing continuous with the bearing 98 into which the trunnions or end of shaft 25 of roll 26 may be positioned when such a roll
 80 is transferred from a set of hangers 23. By means of set screws 99 the sleeve 94 is clamped to the end of shaft 25. Inside of its bearing in bracket 93 the shaft 92 is threaded, and upon this threaded portion is a nut 100 having thereon a washer or collar 90
 85 101 between which and the face of sprocket 90 surrounding shaft 92 is a spring 102 which constantly forces disk 91 into engagement with disk 95. The tension of the
 90 spring and the consequent degree of friction contact between disks 91 and 95 may be regulated by means of the nut and collar 101. By the above means a roll 26 is removably positioned in the uprights 35 and readily connected with driving means which will
 95 effectively rotate the roll but at the same time permit slippage so that the feed of the fabric strip from the rough roller 87 will always be constant. The rear portions of standard 35 are provided with open-ended bearings 103 similar to the bearings 98 and 98'.
 100 A tension member 104 is applied to the shaft 25 adjacent bearing 103 by which a roll 26 on said bearing may be restrained from too rapid rotation, thumb screws 105 regulating the degree of pressure exerted by the tension member. It is noted that the driving mechanism, consisting of sprocket wheel 90, shaft 92, sleeve 94 and friction disks 91 and 95 is readily removable from the bearings formed in the boss 96 and bracket 93 and may be applied to similar parts on the rear portion of standard 35. Since the shaft 86, the bearing 98 and the bearings 103 are at the apices of an equilateral triangle, the sprocket chain 89 will operate to drive a roll 26 when the same is positioned in either set of bearings, and by these means the roll may be wound up from the bearings 98 and 98' and then reversed and wound in the other direction when positioned in the bearings 103.
 105 The operation of so much of my invention as above described will be understood. The sheet of fabric 106 is led from a roll 26 in
 110 115 120 125 130

bearings 103 over a tension roller 107 and around roughened roller 87, beneath another tension roller 108 around roller 55 and to the roll 26 in bearings 98 and 98'. As the machine is driven cards or printed sheets 109 will be delivered between the sets of bands 69 and 70, from which they will pass between rollers 57 and 56 and from which they are delivered upon the apron or sheet 106. This apron, by the means described, is constantly driven at the same rate of speed as the belts 69 and 70, the slip drive formed by the friction disks 91 and 95 compensating for the change of diameter of the roll as the sheet is wound up. The freshly printed cards 109 are thus carried into the body of the roll 26, where they will be retained in fixed position and without possibility of smudging or damage until they are dry. After a run from the press has been thus wound up in a roll 26, the said roll by suitable crane mechanism, not shown, will be suspended from the arms 23 of a truck 22 where the same can be rolled to one side until sufficient time has elapsed for satisfactory drying of the printed cards. After the cards are dry they may be discharged from the apron by running the same in reverse direction upon a roll 26 in bearings 103 as above described, or such roll may be operated in the manner hereinafter described to feed the sheets to the press for further printing and simultaneously to re-roll the freshly printed sheets upon a roll 26 in bearings 98 and 98', as will now be described.

Referring to Figs. 1 and 3, it will be noted that rolls 26 therein shown upon hangers 19 are respectively turned so that the apron or strip 106 is led therefrom in opposite directions. It is the purpose of suspending the rolls in the manner described and taking the apron therefrom to cause said apron to pass through mechanism by which the cards are removed from the apron and delivered to the printing roller. When the cards are taken from the roll, as indicated in Fig. 1, the cards will be delivered to the printing cylinder with the same face up as was printed at the previous time that the cards went through the machine. In multi-color work, as is well-known, the same surface may require from two to five impressions, and it is necessary that the cards shall be slip-sheeted and dried after each impression. It is also common in printing cards of this character to print on both sides of the cards or sheets, in which case to feed from the rolls 26 it will be necessary that the cards be inverted, when the strip 106 will be unrolled in the direction indicated in Fig. 3. In either case the feeding mechanism will be the same. Said feeding mechanism is shown to somewhat better advantage in Fig. 3 and in Fig. 1. Upon the feed table 11 of the press is clamped a frame 110 having parallel

side members 111. In the forward part of members 11 are two pairs of rollers, 112 and 113, and 114 and 115, respectively. The upper of said pairs of rollers, 113 and 114, being spring-pressed upon the lower rollers 112 and 115. Beneath the lower of said pairs of rollers, and positioned so as to engage the lower periphery of roller 115, is an endless belt 116 which runs over a pair of rollers 117 and 118 journaled in side members 111. An obliquely-disposed receiving board 119 is adjustably positioned so that the lower edge thereof comes in proximity with the upper run of belt 116. A curved guide plate 120 extends in spaced relation 80 above receiving board 119, the forward portion of said guide plate curving upwardly so as to extend above the point of junction between rollers 114 and 115. A guide board 121, similar to guide board 130, extends 85 from the forward side of belt 116 to the feed table 11 of the press at a point not far removed from the guide stops 122, where the cards are gripped by the feed cylinder 13 in the well-known manner. The rollers 117, 90 112 and 115 are positively driven, as indicated in Fig. 1. A sprocket chain 123 driven from the shaft of the printing cylinder 13 drives a short shaft 124 on which is a sprocket wheel 125. The sprocket chain 126 95 runs over the sprocket wheel 125 and drives roller 117, and rollers 112 and 115 are driven by a gearing connected with roller 117 so that the peripheries thereof adjacent belt 116 will move in the same direction as adjacent portion of said belt. 100

As shown in Fig. 1, the apron or strip from the roll 26 is led directly backward beneath the lower run of an apron 127 which runs over roller 113 and a roller 128 journaled in the forward ends of arms 129 pivotally connected at their rear ends to the shaft 130 of roller 113. In this manner the apron 127 floats upon the strip 106. When the strip is led in the opposite direction, as shown in Fig. 3, so that apron 127 is not needed, the arms 129 and parts carried thereby will be held suspended out of the way as from rail members 15. In case it is desired to turn over the cards so as to present them with the other side up, the rollers 26 are turned around so that the strip 106 is led therefrom toward the front of the machine, as indicated in Fig. 3. Arms 131 are rigidly but adjustably secured 115 to hangers 19 extending obliquely therefrom a sufficient distance so that the parts carried by said arms will clear the rollers of largest diameter. Journaled in the said arms 131 are rollers 132 and 133, roller 133 120 being a rough-surfaced roller. Secured to the lower portion of arms 131 and to the side frame members 120 are bars 134 having journaled therein a series of rollers 135, and upon the sets of rollers runs an endless 125 130

belt 136. In front of the line of junction between rollers 132 and 133 and the line of junction between roller 133 and belt 136, is a curved passageway 137 formed of an outer 5 guide plate 138 and an inner guide plate 139, the passageway 137 being horse-shoe shape in transverse section. The apron 106 runs beneath roller 132 and around roller 133, and the cards or printed sheets carried 10 on apron 106 are run out into and around the horse-shoe passage 137, coming upon the endless apron or belt 136 between said belt 136 and the sheet or apron 106. It will be 15 noted that in turning the printed cards about the roller 133, as described, the reverse face of said cards is presented between rollers 113 and 112 from what is true when the cards are delivered directly, as shown in Fig. 1. In either case, the cards leave the 20 sheet 106 when they pass between the rollers 112 and 113, and are gripped by the succeeding pair of rollers 114 and 115 and passed under guide plate 111 up the incline receiving-board 119. As the edge of the card 25 passes out from between rollers 114 and 115 it will be carried downward by the periphery of roller 115, which may be made smaller than roller 114 if desired, the lower edge of said card dropping upon belt 116 30 and passing between said belt and the lower periphery of roller 115 from which the card is delivered to an inclined table 121 and from there to the feed table 11.

As shown in Figs. 6 and 7, an alining 35 mechanism is provided by means of which the sheets as they come on to table 11 are drawn sidewise against stop pins 139. To accomplish this a plate 140 is adjustably clamped to table 11 by means of thumb 40 screws 141 extending through slots 142 in said plate 140. The pins 149 are upwardly extended from the plate 140 and are spaced apart forming a guide for a rod 143 which has secured thereto fingers 144 adapted to 45 engage the surface of a sheet upon table 11. A reciprocatory motion is imparted to rod 143 by means of a fork 145 embracing the pin 146 connected with the rod 143 and with a sliding rod 147, the connection of pin 146 50 with rod 143 being adjustable as desired. The fork 145 is on the upper end of vertical shaft 148 journaled on the side of press frame 10. The shaft 148 has thereon an arm 149 pivotally connected to a link 150, in turn connected to an oscillating lever 151 having a cam roller 152 engaging cam 153 55 on the driven shaft 75, said lever 151 being pressed outwardly to hold the roller 152 in engagement with cam 153 by means of a 60 spring 154. As shaft 75 is rotated the vertical shaft 148 will be oscillated and through fork 145 will oscillate bar 143. The end of bar 143, with the friction members 144 carried thereby, is given a gyratory movement. 65 A pin 155 extends to one side so as to en-

gage an upwardly inclined spring member 156 and lift the bar 143. On the other side of bar 143 is another pin 157 which engages, after arm 143 has been elevated by spring plate 156, within a slot 158 in an arcuate 70 member 159. By these means the friction members 144 are held out of contact with table 11 while they are moved inwardly from the edge of said table but drop into contact with said table during the outward 75 stroke, thereby engaging the sheet of paper or card upon the table and drawing the same up against alinement pins 139.

As indicated in Fig. 1, the sheet or apron 106 from roll 26 passes around roller 113 80 beneath rollers 135 and over a roller 160 journaled in arms 131 outside of the lower portion of guide plate 138, and from thence over rollers 161 and 162 journaled between rails 15 and downwardly over rollers 163 85 and 164 journaled at the front of truck frame 34, and from roller 164 around roller 107 and roller 87 to the roller 55, where the same apron 106 that is delivering or feeding cards or sheets to the receiving-table 119 at 90 the rear of the press will be receiving and rolling up printed cards at the front of the press. When the reversing mechanism is used, as shown in Fig. 3, the sheet or apron 106 runs around roller 113 and thence over 95 a roller 165 journaled in rails 15 above rolls 112 and 113, from whence the apron 106 travels over rollers 161 and 162, etc., to roller 55 for receiving and rolling up freshly 100 printed cards.

As illustrated in Fig. 3, the truck 18 may be provided with sockets 166 for the receiving roll 26 and a driving mechanism 167 be provided similar to that consisting of rollers 87 and 107, 108, said driving device being 105 operated by a belt or chain 168 from shaft 75, by which the apron 106 may be directly wound after the same is run between rollers 112 and 113 for feeding the cards instead of carrying said apron forward and winding it 110 up with the freshly printed cards in the roll. Ordinarily, however, when the apron 106 is used for feeding cards to the printing press it will also be used for slip-sheeting or winding the cards up. While my device will be 115 of high utility in slip-sheeting a one-run job, the greatest usefulness of my invention resides in its application to work where the cards or sheets are run through the press two or more times, such as will always be 120 the case where more than one color is used or where the cards or sheets are printed on both sides. In such cases, even though it may be necessary to run the cards through the press six or more times, the cards will 125 need to be handled from the time of beginning the job until the same is completed only once, that is, when they are fed into the press in the first instance. It will readily be apparent how largely this invention will re- 130

duce the cost of handling the finer grade of work where slip-sheeting is always required and usually the work has to be run through the press a number of times. The saving in room and security from damage, alone, are important features of the utility of my invention. When a run of cards has been rolled up in one of the rolls it is transferred to a truck upon the rails 15, where the roll 5 is in the upper part of the room entirely out of the way and may be left for drying as long a time as may be desired without interfering in any way with the other work or requiring space which could be otherwise employed; and when it is desired to unroll 10 the apron for delivering the printed sheets through to the press for a second operation, or to the packaging table, such delivery can be effected with the utmost despatch and 15 without the necessity of moving the piles of cards from one table to another or of any handling.

I claim:

1. In combination with a printing press, 25 an independently movable support provided with two sets of open bearings, a pair of rollers each having trunnions removably positioned in said respective sets of bearings, an interchangeable driving member having 30 means for receiving one of said trunnions and securing the same to said member, sets of holding means on said support for operatively positioning said member in alignment with either of said sets of bearings, common 35 means to rotate said member in either of its said positions, an extended apron connected with said rollers, two sets of guide rollers for causing the apron to travel so that a part thereof presents an upturned receiving surface, and means for delivering freshly printed 40 cards or sheets upon said upturned surface.

2. In combination with a printing press, 45 a support, a roller journaled on said support, a second roller mounted adjacent the delivery end of the press, an extended apron containing printed cards or sheets rolled up on the first roller, means for guiding said apron to deliver the sheets to the feeding 50 mechanism of the press and conducting said apron to the second roller, means for driving said apron at a constant speed, and means for delivering freshly printed cards or sheets from the press and depositing the 55 same upon the apron while the apron is being rolled for winding the cards into the roll.

3. In combination with a printing press, 60 an extended apron and means for rolling the same at a constant speed, means for delivering freshly printed cards or sheets from the press and depositing the same upon the apron while the apron is being rolled for winding the cards into the roll, card-feeding 65 means for the press, and independent means

for unwinding the roll and delivering the cards to the card-feeding means.

4. In combination with a printing press, 70 an extended apron, means for rolling the same and means for delivering freshly printed cards upon the apron to be rolled up therewith, independent means for supporting the roll adjacent the feeding end of the machine, a feeding device comprising a pair of rollers between and around one 75 of which the apron is caused to travel as the roll is unwound, another pair of rollers adjacent the first named pair for receiving the printed sheets and withdrawing them from the apron, and means for winding up 80 the apron as the roll is unwound.

5. In combination with a printing press, 85 an extended apron, means for rolling the same and means for delivering freshly printed cards upon the apron to be rolled up therewith, independent means for supporting the roll adjacent the feeding end of the machine, a feeding device comprising a pair of rollers between and around one of 90 which the apron is caused to travel as the roll is unwound, another pair of rollers adjacent the first named pair for receiving the printed sheets and withdrawing them from the apron, an incline upon which the sheets are deposited from the second pair of rollers, means for feeding the sheets from the incline to the press, and means for winding up 95 the apron as the roller is unwound.

6. In combination with a printing press, 100 an extended apron, means for rolling the same and means for delivering freshly printed cards upon the apron to be rolled up therewith, independent means for supporting the roll adjacent the feeding end of the machine, a feeding device comprising 105 a pair of rollers between and around one of which the apron is caused to travel as the roll is unwound, another pair of rollers adjacent the first named pair for receiving the printed sheets and withdrawing them 110 from the apron, an incline upon which the sheets are deposited from the second pair of rollers, means for feeding the sheets from the incline to the press, means for alining or positioning the sheets, and means for 115 winding up the apron as the roller is unwound.

7. In combination with a printing press, 120 an extended apron, means for rolling the same and means for delivering freshly printed cards upon the apron to be rolled up therewith, independent means for supporting the roll adjacent the feeding end of the machine, a feeding device comprising a pair of rollers between and around one of 125 which the apron is caused to travel as the roll is unwound, another pair of rollers adjacent the first named pair for receiving the printed sheets and withdrawing them 130 from the apron, an incline upon which the

sheets are deposited from the second pair of rollers, an endless belt coöperating with one of the rollers of the last named pair for feeding the cards from the incline to the press, and means for winding up the apron as the roller is unwound.

8. In combination with a printing press, a roll comprising an extended apron having a series of cards or sheets rolled up therewith, card-feeding means for the press, and means for unwinding the roll at a constant speed and delivering the cards from the apron to the feeding means.

9. In combination with a printing press, 15 a roll comprising an extended apron having a series of cards or sheets rolled up therewith, card-feeding means for the press and means for unwinding the roll and delivering the cards from the apron to the feeding 20 means, said feeding means including means for alining or positioning the sheets after the same have been delivered from the apron.

10. In combination with a printing press, 25 a roll comprising an extended apron having a series of cards or sheets rolled up therewith, card-feeding means for the press, a feed table for the press and means for feeding the cards thereto, means for unwinding the roll and delivering the cards to the card-feeding means as the roll is unwound, and 30 positioning mechanism engageable with the card on the feed table and movable transversely to the line of feed of the cards.

11. In combination with a printing press, 35 a roll comprising an extended apron having a series of cards or sheets rolled up therewith, card-feeding means for the press, a feed table for the press and means for feeding the cards thereto, means for unwinding 40 the roll and delivering the cards to the card-feeding means as the roll is unwound, guide stops, and an intermittently movable finger for engagement with the cards on the feed table to draw the same against the guide 45 stops.

12. In combination with a printing press, 50 a roll comprising an extended apron having a series of cards or sheets rolled up therewith, card-feeding means for the press, a feed table for the press and means for feeding the cards thereto, means for unwinding 55 the roll and delivering the cards to the card-feeding means as the roll is unwound, guide stops, an intermittently movable finger for engagement with the cards on the feed table to draw the same against the guide stops, and means to give the finger a gyratory motion so as to cause the same to engage the cards only while moving toward the guide 60 stops.

13. In combination with a printing press, 65 rollers journaled adjacent the feeding and delivering ends of the press, an extended apron connected with said rollers, card-feeding

means for the press, card-delivering means, 65 means for winding the apron upon the roll adjacent the delivery end, and means for guiding the apron while it is being wound so that cards will be delivered thereby to the card-delivering means and will be received and 70 wound up from the card-delivering means.

14. In combination with a printing press, 75 rollers journaled adjacent the feeding and delivering ends of the press, an extended apron connected with said rollers, card-feeding means for the press, card-delivering means, means for winding the apron upon the roll adjacent the delivery end, and means for guiding the apron while it is being wound so that cards will be delivered thereby to the card-delivering means and will be received and 80 wound up from the card-delivering means, said guiding means including devices for presenting the cards to the card-delivering means with either side up as 85 desired.

15. In combination with a printing press, 90 a roll comprising an extended apron having a series of cards or sheets rolled up therewith, card-feeding means for the press, 95 means for unwinding the roll and delivering the cards from the apron to the feeding means, and means for guiding the apron while the same is being unrolled so that the cards may be delivered to the feeding means 95 from either side of the apron as desired.

16. In combination with a printing press, 100 a roll comprising an extended apron having a series of cards or sheets rolled up therewith, card-feeding means for the press, 105 means for unwinding the roll and delivering the cards from the apron to the feeding means, means for guiding the apron while it is being unrolled so that the cards will be delivered to the feeding means from the 105 underside of the apron, and means coöperating with the apron to support the cards while they are being delivered.

17. In combination with a printing press, 110 a roll comprising an extended apron having a series of cards or sheets rolled up therewith, card-feeding means for the press, 115 means for unwinding the roll and delivering the cards from the apron to the feeding means, an endless apron, and a roller about which the extended apron is caused to travel for guiding the same in contact with the upper surface of the endless apron to deliver the cards to the feeding means in reverse position.

18. In combination with a printing press, 120 a roll comprising an extended apron having a series of cards or sheets rolled up therewith, card-feeding means for the press, 125 means for unwinding the roll and delivering the cards from the apron to the feeding means, an endless apron, a roller about which the extended apron is caused to travel

for guiding the same in contact with the upper surface of the endless apron to deliver the cards to the feeding means in reverse position, and a horse-shoe guide for carrying the cards around the last named roller to prevent breaking thereof.

In testimony whereof I affix my signature in presence of two witnesses.

WALTER R. REA.
